CONTACT LENS STERILIZING DEVICE

Michael D. Thomas, Elmhurst, Ill., assignor to
MCD Corporation, Bensenville, Ill.

Filed Mar. 3, 1972, Ser. No. 231,775

Term of patent 14 years

Int. Cl. D24—01; D24—99
U.S. Cl. D83—1 W

FIG. 1

FIG. 2

FIG. 4

FIG. 3

FIG. 5

FIG. 6

FIG. 1 is a perspective view of a contact lens sterilizing device showing my new design;

FIG. 2 is a top plan view thereof;

FIG. 3 is a front elevational view thereof;

FIG. 4 is a side elevation view, the side opposite being a mirror image thereof;

FIG. 5 is a rear elevational view thereof; and

FIG. 6 is a bottom elevational view thereof.

I claim:

The ornamental design for a contact lens sterilizing device, substantially as shown and described.
